UNITED STATES PATENT OFFICE.

LOUIS M. LLORENS, OF LOS ANGELES, CALIFORNIA, ASSIGNOR TO AUTOMATIC WORD COUNTER, INC., A CORPORATION OF NEW YORK.

WORD-COUNTING ATTACHMENT FOR TYPEWRITERS.

Application filed October 12, 1922. Serial No. 594,214.

To all whom it may concern:

Be it known that I, LOUIS M. LLORENS, a citizen of Cuba, residing at Los Angeles, in the county of Los Angeles and State of California, have invented new and useful Improvements in Word-Counting Attachments for Typewriters, of which the following is a specification.

This invention relates to typewriters and has for its broad object to provide means automatically operated by mechanism of the typewriter for registering the number of words written by the typewriter and for registering the action of numeral keys automatically.

It is another object of the invention to provide a registering device operative automatically by the typewriter mechanism and which device is operative, while words are being typewritten, on the stroke of the initial letter key in each word written. A further object is to provide automatically operative registering means in which a stroke of each of the number keys is effective to be registered as a complete word.

Another object of the invention is to provide a simple, reliable, effective and readily operable means for clearing the registered dials of the registering means.

Another object of the invention is to provide means for interrupting the operation of the registering means at will and to provide for the interruption of the actuation of the registering means for only one stroke of a letter key and for interrupting at will the operation, by any of the letter keys and the usual special character keys, of the registering means. And further, it is an object to provide means for interrupting actuation, by all of the keys of the keyboard of the typewriter, of the registering means so that the latter will be rendered neutral or inactive or, so to speak, "cut out".

Another object of the invention is to provide in the registering means, a device whereby the registering wheels may be operated independently of the operation of the keyboard keys as for adding to the registered count as may be necessary in certain cases, as will be explained hereinafter.

A further object of the invention is to provide, in combination with a typewriter, a registering means and instrumentalities re-

spectively for the various letters and special symbol keys, and for the numeral keys of the keyboard. And further, it is an object to provide an instrumentality operative by the usual numeral keys and which is adapted to be automatically shifted by either of the shift keys of the typewriter so that this instrumentality becomes effective dually to register, in the lower position of the typewriter carriage, strokes of the figure keys, and in the upper position of the carriage strokes of the same keys to obtain special characters, such for instance as the " (quote) mark, the # mark, the \$ sign, the % sign, and the & mark, each of which, by the present mechanism, is counted as a word.

An important object of the invention is to provide a unit and organized mechanism, including counting means, which is adapted to be applied bodily to standard and various makes of typewriters substantially without change of construction, or alteration, or machining of any of the parts of the standard machine.

Other objects and advantages will be made manifest in the following specification of an embodiment of the invention illustrated in the accompanying drawings, wherein

Figure 1 is a plan showing one of the conventional keyboard arrangements including the space bar and to which latter an element of the invention is shown combined.

Figure 2 is a vertical section longitudinally of the bank of key levers on line 2-2 of Figure 1, and showing the arrangement of the relative universal "letter" lever actuated comb.

Figure 3 is a section through the bank of key levers and showing the "numeral" lever actuated comb associated therewith.

Figure 4 is a sectional view transversely through a space bar lever showing a bar actuated attachment thereto.

Figure 5 is a plan of the registering means and of the typewriter actuated mechanism thereof; a portion of the typewriter frame being in horizontal section and showing certain parts medially broken away to conserve space.

Figure 6 is a side elevation looking toward the right hand end of the registering means.

Figure 7 is an underneath plan of a reg-

istering means and its associated mechanism and portion of the frame of the typewriter, certain parts being broken away medially.

Figure 8 is a vertical section on line 8—8 of Figure 7, looking in the direction of the arrows and showing the key lever actuated combs in cross section.

Figure 9 is a vertical section on line 9—9 of Figure 7.

10 Figure 10 is a detail longitudinal section of one of the numeral comb shift cams.

Figure 11 is a vertical section on line 11—11 of Figure 5, looking in the direction of the arrows and illustrating mechanism of 15 the registering means, parts of the keys of which are broken away.

Figure 12 is a vertical section showing one of the ram levers in actuated position and the other in normal idle position.

20 Figure 13 is a side elevation of a ratchet wheel and its ram of a totalizing mechanism, the shank thereof being in cross section.

Figure 14 is a vertical section through 25 certain of the shafts and showing the ram lever locking latch in releasing position and actuated by a space bar lever.

Figure 15 is a front elevation, on an enlarged scale, of the totalizing mechanism, 20 the keys thereof being omitted.

Figure 16 is a vertical transverse section on line 16—16 of Figure 15, showing the carrying over mechanism.

Figure 17 is a longitudinal section of the 35 totalizing mechanism on line 17—17 of Figure 16.

Figure 18 is a detail of the adjusting device for the attaching fixtures.

Figure 19 is a view showing diagrammatically 40 three positions of the cut-out lever.

There is a very considerable extent of typewriting performed in which, for various reasons, it is desirable and also the practice to count the words, including numbers, 45 that have been written upon the machine and this I provide means to accomplish, a form of which means being shown and described herewith. A simple method to accomplish this counting consists in arranging means operative by the various keys, with certain exceptions, of the typewriter keyboard, and in my method of word counting I utilize the first stroke in the writing of the 50 initial letter of the word to actuate a registering means which, when the following letter keys in the spelling of a word are actuated, are ineffective, means being provided to automatically interrupt the operation of the registering means after the initial letter 55 stroke of the key in starting the writing of a word.

Key lever actuated instrumentalities are, therefore, combined with the machine, and in the present embodiment such instrumentalities include a plurality, in this in-

stance two, of what might be termed "combs". One of these combs 2 is shown in Figure 2 as having a number of upwardly extending teeth 3, and these teeth are so disposed along the comb bar as to register 70 with respective of the letter keys and their levers 4 of the typewriter; which letter keys are identified in Figure 1 by their respective symbols as are also other keys, such as a key showing a "," and the associated "?" mark, 75 another key showing the upper and lower case period and others as may be mentioned hereinafter. It will be noted that the comb teeth 3 are arranged in spaced groups or fashion the intervening spaces providing 80 for the depression of contiguous numeral key levers 5 without causing operation of the comb 2 as is done by the operation of any of the levers 4 when they engage the contiguous comb teeth 3. 85

In Figure 3 there is shown a comb 6 having upwardly extending teeth 7 which are disposed so as to be engaged by the downwardly pressed numeral key levers 5; the numeral keys being appropriately designated in Figure 1. An important feature of the invention is to provide means operative by the shifting of the usual typewriter carriage from lower to upper case position so that certain of the characters 90 combined on the number type bars, not here shown, and which characters are ordinarily as follows: ", #, \$, %, and &, may be counted, when the keys are struck as words to be included in the total, shown by the registering means of words written.

It might be stated at this point that there are certain symbols which will not be counted as words when their respective keys are operated, and these include the following: 105 the underscore mark usually associated with the numeral key "6", the apostrophe, the two parentheses marks and the asterisk and the hyphen. Also not included as words are strokes of the colon, the semicolon, upper 110 and lower periods, the question mark and the comma and the diagonal line. Strokes of the fraction keys in the lower and upper case positions will be counted as words and the respective combs are accordingly provided 115 with teeth to be engaged by the appropriate levers. To accomplish the operation of the numeral comb 6 when the carriage has been shifted and when certain of the symbols associated with the numeral keys are actuated, certain 120 of the teeth 7 of the comb 6 are shown as wider than others, the widened teeth 7 being engageable by given keys when the numeral comb 6 is shifted, but clearing the keys over the narrow teeth. 125

The letter comb 2 extends longitudinally beneath the keyboard and is supported on the outer ends of arms 8 which are secured on a rock shaft 9, the ends of which are journaled in bearings, one of which is in 130

dictated as a plate 10 having a bottom leaf secured by screws 11 and 12 to the bottom of the side frame members 13 of the typewriter frame, which is usually provided with tapped holes to receive screws for various attachments not necessary to be described. The opposite end of the rock shaft 9 extends into an upwardly extending bearing plate 15 forming a portion of the casing including the registering means and forming suitable bearings for parts thereof. The rock shaft 9 has secured to it a forwardly and downwardly extending lever 16 and this is provided with a laterally projecting pin 17 engaging a lever 18, the swinging end of which is provided with a slot 19 in which the pin 17 slides and engages the edge walls of the slot. The lever 18 has a hub 20 which is secured to a hollow shaft 21, Figure 9. This hollow shaft 21 is rotatively supported on an inner rock shaft 22, each of these shafts being journaled in up-standing plates of the casing above referred to and generally indicated at 25. The train 25 of levers connecting the letter comb 2 and the hollow shaft 21 as above described are all controlled by a recovering device shown as including a spring 23 which is attached to the swinging end of the lever 18 and to a fixed part as a pin 24 of the casing 25. It will be seen that when any of the keys, having levers engaging the letter comb 2, are depressed that the hollow shaft 21 will be rotated slightly against the tension of the spring 23 and as soon as the actuated key is released, the letter comb train is recovered or reset to the normal position unless otherwise prevented as will be hereinafter explained, by the action of the spring 23.

The numeral comb 6 has attached to it rearwardly extending arms 26 which are secured on a rock shaft 27 extending longitudinally beneath the bank of key levers and having a bearing in the attaching plate 15 and also having a bearing in the side plate 15 of the casing 25. The rock shaft 27 is designed to have longitudinal movement and is provided with stop collars 28 which respectively engage contiguous cam bars 29 which are slotted at 30, Figure 9, to ride upon the shaft 27 transversely, and which, when actuated, thrust the shaft 27 in the direction of the arrow, Figure 10, against the reaction of a spring 30 normally pushing the shaft 27 to a given position so as to hold the teeth 7 of the comb 6 in register below the numeral key levers. There is one of the cam bars 29 adjacent each end of the rock shaft 27, and these form means operated by the shift keys of the typewriter keyboard to accomplish the shifting of the rock shaft 27 so that the teeth 7 of the comb will be present under certain of the numeral keys to accomplish a registration of the stroke of certain of these keys

during the operation of the typewriter; the effective keys, in the shift position being thus designated with the following marks: —#—%— and the —&—, these and all other character-writing keys being herein-after referred to as "keyboard elements".

Secured on the rock shaft 27 is a lever arm 31 and this is provided with a pin 32 engaging a lever 33 provided in its swinging end with a slot 34, the edge walls of which are engaged by the pin 32 and in which slot the pin slides. The lever 33 is provided with a hub 35, and this is secured as by a set screw 36 on the previously mentioned rock shaft 22 and extends through the hollow shaft 21. The lever train connected to the numeral comb 6 is normally retracted to an initial position by any suitable means consisting, in the present case, of a spring 37 attached to the swinging end of the lever 34 and to a contiguous fixed part, as pin 38 mounted in the casing 25.

From the above it will be seen that I have provided a mechanism including instrumentalities operative by certain of the several key levers of the keyboard and wherein a means is provided also for the axial shifting of one of the instrumentalities so as to give it two positions and enable the operation thereof by a set of keys when these are actuated in either lower or upper case functions.

I have provided also a totalizing or registering means operated by the aforesaid organization so as to keep count of the number of words or actions which may be counted as words during the operation of the typewriter, and a simple, practicable, effective, reliable and substantial form of counting means is herein shown in one embodiment as follows:

In the casing 25 there is journaled a transversely extending shaft 40 which, in the present case, is shown as noncircular and on its outer end is provided with a pinion 41 engaged by a segment of a gear 42 pivoted on a stud 43, Figure 6, the hub of the segment 42 being flattened as at 44. The segment is provided with a handle 45 projecting outwardly from the casing and enabling the ready operation of the rack 42 which is so proportioned as to give the pinion 41 one complete revolution for each full stroke of the segment. Nonrotatably mounted on the shaft 40 is a series of discs or carry-over wheels 46 provided with recessed peripheral portions 47 terminating in hook-like ends 48, Figure 16. The several carry-over discs 46 are shown as countersunk in the adjacent faces of totalizing wheels 49 which are axially spaced along the shaft 40, and each of which is provided with a rigid ratchet wheel 50. The ratchet wheels substantially form hubs for the totalizing wheels 49, and these hubs are turnably

mounted on spacer bushings 51 through which the pinion shaft 40 extends, thus enabling the rotation of the totalizing wheels 49 independently of the pinion shaft 40.

5 Spring 42' pulls segment 42.

On one side face of each of the totalizing wheels 49 there is provided a pivot pin 52, and on this is pivoted a transferring pawl 53 which has a hook end normally pressed 10 downward by a spring 54 so as to engage a tooth of the ratchet wheel 50 of the totalizing wheel 49 of the next higher order when this is permitted by the carry-over discs 46. The pawls 53 are each provided with 15 a laterally extending pin 55 extending into a pocket 56 provided therefor in its totalizing wheel 49, the pins 55 projecting through the respective wheels and being engaged by the springs 54 which are provided on the opposite side of the wheels, as clearly shown 20 in Figure 17. It will thus be seen that if the unit totalizing ratchet wheel 50 is given an impulse from the zero position, it will turn its respective totalizing wheel 49 one 25 step. After nine steps have been made by the totalizing wheel, its transfer pawl 53 rides off of the periphery of the carry-over or carrying disc 46, and as the pin 55 of the wheel pawl drops into the recess 47 of the next higher transfer wheel 46, the hook 30 of the pawl 53 engages the contiguous tooth of the next higher ratchet wheel 50. And then on the tenth stroke of the lower order of totalizing wheel 49, the hook pawl 53 35 of the actuated wheel becomes operative upon the engaged ratchet 50 and will turn this one step. The next successive movement of the lower order totalizing wheel causes the ratchet pin 55 thereof to ride out of mesh 40 with the engaged ratchet 50 and clear the same without a transferring action; this being caused by the cam action of the face of the recess 47 in the carry-over disc which is held stationary by its shaft 40.

45 Check means are provided for preventing reverse action of the transfer or carry-over ratchets 50, and such means is shown in Figure 16 as including a series of upwardly extending latches 57, the lower ends of 50 which are pivoted on a pivot rod 58. The brake latches 57 are normally pulled into locking position by a yielding means such as a spring 59 fixed to a convenient fastening at one end and attached to the respective 55 brake latches 57 at the opposite end. When the several transfer ratchets are rotated in one direction their brake latches yield, but the ratchets are prevented from a reverse rotation by interlocking of the brake latches 60 with the teeth of the ratchets. The brake latches consists of simple upstanding members which are guided and laterally supported in guide plates 60 and 61 which are slotted to receive the latches. In the present 65 construction, the guide plates are rigidly

secured to each other in superposed position and are attached to the contiguous ends of parallel arms of a yoke frame 62 which is pivoted on the pivot shaft 58, and when any one of the ratchet wheels 50 is rotated this 70 results in a tilting of its brake latch 57 and this engages the upper guide plate 60, which being secured to the yoke frame 62 causes this latter to tilt upwardly at its inner end. Secured on the inner end of the 75 yoke frame 62 is an upwardly extending member 63 which has the function of locking means which actuate the unit or first ratchet wheel of the series.

The totalizing mechanism above described 80 is adapted to be actuated by the action of the rock shafts 20 and 22 which are actuated by the lever combs above described. These rock shafts 20 and 22 extend into the casing 85 of the totalizing mechanism and the tubular rock shaft 20 has secured to it an upwardly extending lever 70, Figure 12, and this is provided with spaced horns 71 projecting from its upper end, and these horns are adapted to swing toward and from a stop pin 72 secured to the contiguous wall of the 90 casing 25. The inner rock shaft 22 has secured to it a lever arm 73 which has upwardly projecting horns 74 also designed to engage the stop pin 72.

95 The lever 70 is pivotally connected at 75 to the contiguous end of a horizontally extending bar hereinafter called the ram 76, the forward end of which is provided with shoulders or teeth 77, the foremost one of 100 which is, in the retracted projection of the ram, designed to rest contiguous to the lowermost tooth of the first ratchet wheel 50 of the counting mechanism. The ram 76 is normally pulled to a retracted and upper 105 engaging position by a spring 78, Figure 11, and is thereby held in engagement with the primary ratchet wheel 50. Upon operation of the letter comb 2, the hollow rock shaft 20 is oscillated and this results in 110 forcing the lever 70 forwardly and throws the ram 76 forwardly as is shown in Figure 13, so that the primary ratchet wheel 50 is turned one step. This initial step rotation causes the unit counting wheel 49 to take 115 a one-tenth revolution so that its peripheral index number will be set to indicate a stroke of a key lever.

120 A feature of the present invention includes means whereby the actuating ram 76 is locked against action except by the first stroke of a letter key in the spelling of a word or in striking a single letter word, such as for instance the letter "I" which is, of course, a complete word. The mechanism is designed to permit the writing of a word of any number of letters and to cause register of the whole word but once. This is accomplished by means under the control 125 of the space bar 100 of the typewriter.

The space bar control means includes an automatic latch 80 which is secured on a rock shaft 81 extending horizontally under the keyboard. The extended end of the rock shaft 81 is provided with a lever arm 82 having a lateral shoulder 83 positioned beneath the contiguous lever arm 101 of the space bar 100, so that when the space bar is pushed down, its lever 101 engages the lever arm 82 of the rock shaft 81, and this is rocked to lift the latch 80 from engagement with a pin or shoulder 84 provided on the actuating lever 70. The rock shaft 81 with its latch 80 is yieldingly pressed into locking position by suitable means which may consist of a compressed spring 85, Figure 14, engaging a lever 86 secured on the rock shaft 81. When the actuating lever 70 is thrown on its operating stroke to push the ram 76 and turn the primary ratchet wheel 50, the pin 84 passes beneath the contiguous hook of the latch 80 as is shown in Figure 12, and the latch becomes effective instantly to engage the pin 84 and hold the lever 70 in the thrown position so that the lever 70 cannot return to idle position as pressure of the finger is removed from the key of the keyboard which initiated the action of the lever 70 and its ram 76. Thus the holding latch 80 remains effective in locking position until it is disengaged by action of the space bar 100, as shown in Figure 14. From this it will be seen that as the initial key of any word is struck, the first action is utilized to actuate the counting mechanism and the ram 76 is held out of commission while the rest of the letter keys, necessary in the spelling of a word, are actuated. Where the word consists of one letter or any multiple, as soon as the space bar 100 is struck in completing the word and to shift the carriage of the typewriter, then the locking latch 80 releases the lever 70 and its ram 76, and these parts are restored automatically to the idle position in readiness to be again actuated.

The inner shaft 22 is actuated by the numeral and certain other keys and therefore rocks the lever 73 to which is connected a ram or push rod 87 which projects forwardly and operatively engages the primary ratchet wheel 50 in the same manner and action as with respect to the previously described ram 76: these two rams lying side by side beneath the primary ratchet as clearly shown in Figure 15, each having a spring 78 to yieldingly hold it in engagement with the primary pinion 50. As distinguished from the action of the lever 70, the numeral comb actuated lever 73 is not designed to be locked out of action as is the lever 70, since it is desirable to count each stroke of any numeral lever excepting the "0" lever as one complete word. For instance, in the typing of the number "999", the machine would register the three separate strokes of the lever "9" as words. In the writing of the numeral "10", the operation of the "L" letter would become effective to actuate the primary ratchet wheel 70 of the unit counting wheel and then the following stroke of the "0" lever when made would not be counted as a word for the reason that the numeral "10" is, in the present system, considered but one word. A further special matter is that the numerals "11" to "19" are counted as one word and this is secured by providing means for cutting out or negativing the action of the key levers upon the counting means.

The cut-out means includes a key lever 88 fulcrumed on a rock shaft 89, Figure 11, and being normally thrown to the normal position as by means of a spring 90. Secured on the rock shaft is an upwardly extending lever arm 91 which is provided with a laterally extending pin or shoulder 92, and this extends transversely across and somewhat above the upper edges of the rams 76 and 87. By pressing down the cut-out lever 88, the lever arm 91 swings down and is operative to first depress the ram 76 so as to carry it out of engagement with the unit count wheel ratchet 50. Therefore, it will be seen that if a letter key of the keyboard is struck while the ram 76 is disengaged by the cut-out means, the primary or unit ratchet wheel 50 will not be actuated. Therefore, this device serves to neutralize the action of the mechanism when any of the letter keys are actuated. The cut-out device is adapted to be locked in effective position and automatically released, and to that end the lever arm 91 is shown as provided with a latching pawl 93 pivoted at 94 on the arm 91. The latch pawl 93 has a shouldered end 95 which is designed to interlock with a stop pin or shoulder 96 fixed on a convenient rigid portion of the counting mechanism casing or frame. The cut-out key 88 is designed to have three several positions, the first of which is the idle or normal position shown in full lines in Figure 11; the second of which is the dotted line position of Figure 11 wherein the locking pawl 93 is in engagement with the stop shoulder 96 which prevents the cut-out lever 88 from automatically resuming normal position until it is automatically released from its second position by suitable means. The automatic releasing means includes a kick-off pin or shoulder 97 secured to or formed upon the actuating lever 70 and in such position that when this lever 70 is actuated it will engage the contiguous cam shaped end of the lever 93 with the result that this lever is lifted from locking engagement with the shoulder 96 and the cut-off lever 88 is automatically restored to its normal position.

As above explained, the shifting of the cut-out lever to the second position is effected to negative the operation of the ram 76 upon the unit ratchet wheel 50.

It is desirable, in some cases, to negative not only the effect on the counting machine of the letter keys of the keyboard, but also to negative all of the other keys that actuate the comb 6. To that end the cut-out lever 88 is designed to have a final and third or lowermost position as is indicated diagrammatically in Figure 19, at which time the disconnecting pin 92 of the lever arm 91 engages and depresses the ram 87 also from the unit or primary ratchet wheel 50. Therefore, all of the keys of the keyboard may be operated without any actuation of the counting mechanism. The cut-out lever 88 is designed to be locked in its final keyboard cut-out position and this is readily accomplished by providing in the shank of the lever 88 an aperture 99, and when the lever 88 is in its lowermost position, it can be shifted slightly laterally to engage a contiguous projection as the end of shaft or rod 58 mounted in the casing or frame 25.

In typing the numeral "11," the letter key "L" is struck once to secure a word count action of the counting means and then the cut-out key 88 is depressed to the second position to negative the second stroke of "L" lever in completing the numeral "11." This second letter key stroke unlocks the pawl 93 and releases the key 88. "11" is thus registered as one word.

In typing numerals "12" to "19" inclusive these are each counted as one word by first depressing the cut-out lever to second position and then striking the "L" key. This restores the cut-out key 88 without an action of the counting wheels. The key of the next digit is then struck and this action is registered as a word by the counting mechanism.

It is desirable to provide means for the manual actuation of the word counting means in various cases of ordinary or special occurrence. For example, when typing the numeral "2039" the naught is not registered as a word since it is not desirable to register "10" nor multiples thereof to "90" as more than one word.

This supplementary adding means includes a lever 105 pivoted at its rear end on a pivot pin 106 and normally elevated to an uppermost position as by a spring 107, Figure 6. The uppermost position is determined as by engagement with the exposed end of the shaft 40 of the pinion 41. Under the rear end of the adding lever 105 is a finger 108 which is fixed on the center shaft 22 to which is secured the upwardly extending lever 73 actuating the ram 87. Therefore, by the application of a finger to the adding lever 105, this, when pressed

downwardly, rocks the shaft 22 and this in turn gives a stroke to the ram 87 and the unit ratchet wheel of the counting wheels is given a step. It will be seen that the adding key 105 can be depressed at any time and will result in the addition of an additional word to the total registered on the totalizing wheels 49. This adding lever has any suitable stop device to limit its downward movement such, for instance, as a lug 109 secured to its under edge and which is designed to engage the bottom of the housing 25.

All of the totalizing wheels 49 are adapted to be restored to an initial blank position, the cipher indexes thereof aligned preparatory to beginning a new count, and this is accomplished by the simple forward pulling of the stem 45 which is connected to the segment 42, this in turn spinning the clearing shaft 40 whereby the several clearance discs 46 are concurrently rotated to bring the clearance shoulders 48 thereof into engagement with the carry-over pins 55 on the pawls or clicks 53 of the several totalizing wheels 49.

As previously disclosed, the hub of the clearance segment 42 is provided with a flattened surface 44, and this is designed to depress a tripping arm 110 that is secured on the contiguous end of the latch rock shaft 81 so that in the event that at the moment the counting mechanism is cleared by the segment 42, if the locking latch 80 is holding the lever 70, the latter will be released by the action of the tripping arm 110 when the segment 42 is thrown forward in the clearing stroke. This restores the entire mechanism to the normal "ready" position in condition for the next keyboard action.

Means are provided for preventing the overthrow of the several totalizing wheels 49 when the clearing segment 42 is thrown and which means is shown as including in Figure 16 a transverse bar 111 disposed substantially in the horizontal plane of the axis of the wheels 49 and which is secured to the upper ends of upwardly extending lever arms 112 on a rock shaft 113. A yielding connection is made between the bar 111 and a contiguous shoulder, as for instance the inner end of the stem 45. This yielding connection is here represented as including an upwardly extending spring arm 114 having a transversely bent end 115 playing in a window 116 in the side wall of the casing 25; the spring end 115 being engaged by the swinging end of the stem 45 as the latter is moved to clear the totalizing mechanism. The spring 114 then becomes yieldingly effective to throw the stop bar 111 so that prongs thereof will project into the path of the transfer clicks 53 of the totalizing wheels 49 as these are restored to the clear position.

- The key levers of the keyboard which are respectively designated one by a comma and a question mark, one by upper and lower case periods, and one by a colon and a semi-colon, are not designed to actuate the counting mechanism, but instead are utilized as a means alternative with the space bar 100 to release the lock latch 80 after the completion of a word in a manner similar to the releasing of the locking latch when the space bar is actuated. Means for utilizing these just mentioned keys includes an engagement strip or plate 120, Figures 1 and 4, which is secured to the space bar lever 101. This engagement device is in the form of laterally extending lugs and may be attached to the space bar lever 101 as by a simple form of clamp 121 in such position as to be engaged by this space bar lever when it is actuated.
- When the shift keys (so designated in Figure 1) are actuated, the cams 29 are thrown to effect a longitudinal movement of the rock shaft 27 to secure the object above described of placing the numeral comb 6 so that certain of the numeral keys of the keyboard will be utilized in action to actuate the counting means. The cams 29, Figures 9 and 10, are actuated by levers 122 of the respective shift keys. These levers respectively engage crank levers 123 mounted on pivot pins 124, the lower ends of the downwardly extending arms of the cranks 123 being connected to the contiguous ends of the cam members 29. Downward pressure on a shift key lever 122 results in pulling a respective cam 29 forwardly and this will shift the rock shaft 27 axially to the desired position. The usual returning movement of the shift keys effects a restoration of the cams 29 and releases the rock shaft 27 so that it will return under the impulse of its spring 30 to the normal position.
- It will be seen that any tendency of the ratchet wheels to be overthrown by the action of the rams will be prevented by the upward movement of the abutment member 63 which is actuated by the ratchets when they tilt the upwardly extending latches 57, since the member 63 is designed to encounter downwardly extending means in the form of lugs on the lower front end portions of the rams 76-87. The member 63 thus forms a stop to prevent the rams from springing downwardly out of mesh with the contiguous ratchet. The downwardly extending shoulders 76' on the ram 76 clear the abutment member 63 when the ram 76 is in its locked position under control of the latch 80. This enables the ram 87 to be given its regular full stroke to actuate the primary ratchet wheel and to be engaged by the abutment member 63 in its usual function of preventing the ratchet wheel from being overthrown.
- Further embodiments, modifications and changes may be resorted to within the spirit of the invention as here claimed.
- What is claimed is:
1. In a typewriter having a keyboard, a counting means for registering the actions of the typewriter in the writing of words or word equivalent, mechanism actuated by elements of the keyboard and operative upon the counting means, and a cut-out key for rendering said mechanism inoperative upon the counting means so that the keyboard elements may be actuated once only independently of the counting means, thereafter automatically returning to registering position.
  2. In a typewriter having a keyboard, a counting means for registering the actions of the typewriter in the writing of words or word equivalent, mechanism actuated by elements of the keyboard and operative upon the counting means, and a cut-out key for rendering said mechanism inoperative upon the counting means so that the keyboard elements may be actuated independently of the counting means, said mechanism including parts directly effective upon the counting means, said cut-out key being operative upon said parts and automatically released after each first operation.
  3. In a typewriter having a keyboard, a word or word equivalent counting means, mechanism actuated by elements of the keyboard for operating the counting means, and a device attached to the space bar to be actuated therewith for setting the counting means preparatory to actuation by the said mechanism.
  4. In a typewriter having a keyboard, a word or word equivalent counting means, mechanism actuated by elements of the keyboard for operating the counting means, and a device attached to the space bar to be actuated therewith for setting the counting means preparatory to actuation by the said mechanism, said device being engageable by certain of the keys of the keyboard to effect the same function as that of the space bar as to the counting means.
  5. In a typewriter having a keyboard, a counting means for indicating the total number of words or word equivalent written during the operation of the typewriter, mechanisms each being actuated by a separate group of elements of the keyboard for operating the counting means, a positive lock means automatically applied to render said mechanism inoperative on the counting means during the completion of a word following the stroke of the keyboard element writing the first letter of the word.
  6. In a typewriter having a keyboard, a counting means for indicating the total number of words or word equivalent written during the operation of the typewriter, a mechanism actuated by elements of the keyboard for operating the counting means, a lock

- means to render said mechanism inoperative on the counting means following the stroke of the keyboard element writing the first letter of the word, said lock means being releasable by certain elements of the keyboard, and including an independent lever operative by the space bar.
7. In a typewriter having a keyboard, a counting means for indicating the total number of words or word equivalent written during the operation of the typewriter, a mechanism actuated by elements of the keyboard for operating the counting means, an automatic positive lock means to render said mechanism inoperative on the counting means following the stroke of the keyboard element writing the first letter of the word, said lock means being releasable by certain elements of the keyboard.
- 10 8. In a typewriter having a keyboard, means for indicating the total number of words or word equivalent written during the operation of the typewriter, a mechanism actuated by elements of the keyboard for operating the counting means, a positive lock means to render said mechanism inoperative on the counting means following the stroke of the keyboard element writing the first letter of the word, said lock means being releasable by means comprising an element secured to a space bar lever and engageable by certain elements of the keyboard whereby the actuating mechanism is set for further operation of said keyboard elements.
- 15 9. In a typewriter having a keyboard, means, a mechanism for operating said means, said mechanism including instrumentalities comprising a plurality of combs one of which is actuated by one group of keys of the typewriter keyboard, and another of which is operated by another group of keys of the keyboard, means for locking one of said instrumentalities and an independently mounted, space bar actuated lever for releasing the locked instrumentality.
- 20 10. In a typewriter having a keyboard, means, a mechanism for operating said means, said mechanism including instrumentalities one of which is actuated by one group of keys of the typewriter keyboard, and another of which is operated by another group of keys of the keyboard, and means actuated by the shift keys of the keyboard to longitudinally shift one of the instrumentalities to a second position so as to become operative, in the new position by certain of its group of keys.
- 25 11. In a typewriter having a keyboard, means, a mechanism for operating said means, said mechanism including instrumentalities one of which is actuated by one group of keys of the typewriter keyboard, and another of which is operated by another group of keys of the keyboard, one of the said groups of keys consisting of the letter keys and the other consisting of the numeral keys, and a device attachable to a space bar to engage other keys.
- 30 12. In a typewriter having a keyboard, means, a mechanism for operating said means, said mechanism including instrumentalities one of which is actuated by one group of keys of the typewriter keyboard, and another of which is operated by another group of keys of the keyboard, and a cut-out key whereby the actions of the respective groups of keys are concurrently rendered ineffective upon the counting means.
- 35 13. In a typewriter having a keyboard, means, a mechanism for operating said means, said mechanism including instrumentalities one of which is actuated by one group of keys of the typewriter keyboard, and another of which is operated by another group of keys of the keyboard, and a cut-out key for rendering one of said instrumentalities ineffective upon the counting means when said device is set in an initial cut-out position.
- 40 14. In a typewriter having a keyboard, means, a mechanism for operating said means, said mechanism including instrumentalities one of which is actuated by one group of keys of the typewriter keyboard, and another of which is operated by another group of keys of the keyboard, and a cut-out key for rendering one of said instrumentalities ineffective upon the counting means when said device is set in an initial cut-out position, said cut-out device being automatically released from its initial cut-out position by the next action of its controlling instrumentality.
- 45 15. In a typewriter having a keyboard, means, a mechanism for operating said means, said mechanism including instrumentalities one of which is actuated by one group of keys of the typewriter keyboard, and another of which is operated by another group of keys of the keyboard, and a cut-out device for rendering one of said instrumentalities ineffective upon the counting means when said device is set in an initial cut-out position, said cut-out device being automatically released from its initial cut-out position by the next action of its controlling instrumentality, the cut-out device including a latching means to hold it releasable in the initial cut-out position, and a kick-off element forming a part of the said mechanism for tripping the latching means upon the next stroke of its controlling instrumentality.
- 50 16. In a typewriter having totalizing means for counting and indicating the number of words or word equivalents written by the typewriter keys, a mechanism including parts operative by elements of the keyboard for actuating said means, a positive control device for locking said mechanism

after the initial key lever action in typing the first letter of a word, a keyboard element controlled means for actuating said positive device to release said mechanism for action at the beginning of the spelling of another word, and means for "clearing" the counting means and for tripping the control device to restore the mechanism to ready position.

10 17. A word counting attachment for typewriting machines including a totalizing means and a mechanism adapted to be exposed when attached to the machine so as to be operative by elements of the keyboard of 15 the typewriting machine whereby the words or word equivalents written by the machine are counted by the counting means, said means including a plurality of combs disposed at the front ends of the keyboard elements.

20 18. A word counting attachment for typewriting machines including a totalizing means and a mechanism adapted to be exposed when attached to the machine so as to be operative by elements of the keyboard of the typewriting machine whereby the words or word equivalents written by the machine are counted by the counting means, said mechanism including a cutout key lever 25 having a position for neutralizing the action of only certain elements of the keyboard upon the counting means.

25 19. A word counting attachment for typewriting machines including a totalizing means, and a mechanism adapted to be exposed when attached to the machine so as to be operative by elements of the keyboard of the typewriting machine, said totalizing means being provided with means to render 30 it inoperative by keyboard action and including a cutout key.

30 20. A word counting attachment for typewriting machines including a totalizing means, a mechanism adapted to be exposed when attached to the machine so as to be operative by elements of the keyboard of the typewriting machine, said totalizing lock means being provided with means to render 35 it inoperative by keyboard action, and a clearing device operatively connected to said mechanism and combined with the totalizing means for restoring the totalizing wheels to zero position and simultaneously releasing said lock means.

35 21. A word counting attachment for typewriting machines including a totalizing means, a mechanism adapted to be exposed when attached to the machine so as to be operative by elements of the keyboard of the typewriting machine, said totalizing means being provided with means to render it inoperative by keyboard action, and a clearing device combined with the totalizing means for restoring the totalizing wheels to 40 zero position and having means operative to

release certain parts of said mechanism from a locked position.

22. A typewriter attachment having, in combination, a counting means for indicating the total number of words or word equivalents written during the operation of the typewriter, a mechanism including "combs" actuated by selected groups of keyboard levers for actuating the counting means, and means connected to the shift key levers of the typewriter to longitudinally shift one of the said combs into association with a different group of keyboard levers.

23. A word counting attachment for a typewriting machine, including a totalizing means, a set of "combs" adapted to be disposed under the front ends of and actuated by respective groups of key levers of the typewriter, one of said groups consisting of letter keys; means for locking the letter key actuated comb; and independent, space bar actuated means to release the locking means.

24. In a typewriter having a keyboard totalizing means for counting and indicating the number of words or word equivalents written by the typewriter keys, a mechanism including parts operative by elements of the keyboard for actuating said means, a positive control device for locking said mechanism after the initial key lever action in typing the first letter of a word, and a keyboard element controlled means for actuating said positive device to release said mechanism for action at the beginning of the spelling of another word, said release being operable through a punctuation key.

25. In a typewriter having a keyboard, a means for counting and indicating the number of words or word equivalents written by the machine, keyboard controlled parts for actuating said means, a device for locking said parts after the first letter action, and a keyboard controlled means to release said parts for action at beginning of another word.

26. A word counting attachment for typewriting machines including a totalizing means, a mechanism adapted to be exposed when attached to the machine so as to be operative by elements of the keyboard of the typewriting machine, and a clearing device combined with the totalizing means for restoring the totalizing wheels to zero position and having means operative to release certain parts of said mechanism from a locked position.

27. A word counting attachment for typewriting machines including a totalizing means, a mechanism adapted to be exposed when attached to the machine so as to be operative by elements of the keyboard of the typewriting machine, said totalizing means being provided with means to render it inoperative by keyboard action, and a clearing device operatively connected to said

mechanism and combined with the totalizing means for restoring the totalizing wheels to zero position and for resetting the said mechanism.

- 5 28. A word counting attachment for typewriting machines including a totalizing means and a mechanism adapted to be exposed when attached to the machine so as to be operative by elements of the keyboard of the typewriting machine whereby the words or word equivalents written by the machine are counted by the counting means, said mechanism including a cutout key lever having a position for neutralizing the action of certain elements of the keyboard upon the counting means, and a locking pawl for releasably holding said lever in its neutralizing position, a means comprising a rock shaft carrying a lever arm provided

with means for engagement beneath a space bar lever, for automatically releasing said locking pawl upon the striking of said space bar.

29. A word counting attachment for typewriting machines including a totalizing means, and a mechanism adapted to be exposed when attached to the machine so as to be operative by elements of the keyboard of the typewriting machine, said totalizing means being provided with means to render it inoperative by keyboard action and including a cutout key, said mechanism including two combs engageable by all keyboard elements and which are both held cut out by said key.

In testimony whereof I have signed my name to this specification.

LOUIS M. LLORENS.
